UNITED STATES PATENT OFFICE

154,112

DESIGN FOR A COOKING RANGE CONTROL PANEL UNIT

Montgomery Ferar, Detroit, Mich., assignor to
Sears, Roebuck and Co., Chicago, Ill., a corpora-
tion of New York

Application December 10, 1947, Serial No. 143,092

Term of patent 7 years

(Cl. D81—25)

To all whom it may concern:

Be it known that I, Montgomery Ferar, a citizen of the United States of America and a resident of Detroit, county of Wayne, and State of Michigan, have invented a new, original, and ornamental Design for a Cooking Range Control Panel Unit, of which the following is a specification, reference being had to the accompanying drawing, forming a part thereof.

Fig. 1 is a front perspective view of a cooking range control panel unit, showing the new design;

Fig. 2 is a transverse sectional view through the

panel taken approximately at line 2—2 of Fig. 1;

Fig. 3 is a transverse sectional view taken approximately at line 3—3 of Fig. 1; and

Fig. 4 is a transverse sectional view taken approximately at line 4—4 of Fig. 1.

The invention claimed is:

The ornamental design for a cooking range control panel unit, substantially as shown,
MONTGOMERY FERAR.
